UNITED STATES PATENT OFFICE.

HENRY CHRISTOPHER, OF BROOKLYN, NEW YORK.

HORSESHOE-PAD.

SPECIFICATION forming part of Letters Patent No. 698,904, dated April 29, 1902.

Application filed May 8, 1901. Serial No. 59,202. (No model.)

To all whom it may concern:

Be it known that I, HENRY CHRISTOPHER, a citizen of the United States, residing at Brooklyn, in the county of Kings and State 5 of New York, have invented certain new and useful Improvements in Horseshoes and Horseshoe-Pads, of which the following is a full and complete specification, such as will enable those skilled in the art to which it applies 10 to make and use the same.

This invention relates to horseshoes and horseshoe-pads; and the object thereof is to provide improved devices of this class by means of which the feet of a horse will be 15 protected against injury and prevented from slipping, a further object being to provide a horseshoe and pad therefor which completely covers the bottom of the feet and which is provided with means for ventilating the feet 20 when the shoe and pad are in use; and with these and other objects in view the invention consists in a horseshoe provided with a pad constructed as hereinafter described and claimed.

25 The invention is fully disclosed in the following specification, of which the accompanying drawings form a part, in which the separate parts of my improvement are designated by the same reference characters in each of 30 the views, and in which—

Figure 1 is a bottom plan view of a horseshoe provided with my improved pad; Fig. 2, a top plan view of the pad removed from the shoe; Fig. 3, a top plan view of one part 35 of the pad; Fig. 4, a cross-section on the line 4-4 of Fig. 2, and Fig. 5 is a sectional view of a detail of the construction.

In the drawings forming part of this specification I have shown at 6 a horseshoe in which 40 is placed a pad 8, said pad being so formed as to entirely fill the shoe and to project backwardly beyond the ends of the sides of the shoe, as shown at 9, although this feature is not an essential element of my invention, 45 as the sides of the shoe may be extended backwardly as far as the pad, if desired. The shoe 6 is also shown slightly longer on one side than on the other, the object of this construction being to weight one side of the 50 foot more than the other when necessary.

The pad 8 consists of a top portion 7^a, of leather, which entirely covers the body por-

tion of the pad and also the shoe, and the body portion 7^b of the pad consists, preferably, of rubber, rubber and canvas, or other 55 suitable material and is provided with a top flange 7^c, which fits between the sides of the shoe and the top portion 7^a of the pad. The central portion of the pad is open, as shown at 7^d, and placed therein is a hollow cushion 60 8', composed of rubber, rubber and canvas, or similar material and which is closed at the bottom, open at the top, and covered by the top portions 7^a of the pad, which is composed of leather, as hereinbefore described. 65

In Fig. 3 of the drawings I have shown the body of the pad with the leather covering or top 7^a removed, and the body portion of the pad is provided with a groove 9 around the central opening 7^d, in which are formed perforations 10, which communicate with corresponding perforations 11 in the top portion 7^a of the pad, and said top portion 7^a of the pad is also provided centrally with perforations 12, which communicate with a space within the 75 central cushion 8', and around the groove 9 in the body portion 7^b of the pad are formed perforations 13, which communicate with corresponding perforations 14 in the top portion 7^a of the pad. The body portion 7^b of the pad is 80 also provided in the front portion thereof with a calk-holder 15, and two similar calk-holders 15 are set into the rear portions of the pad, and each of these calk-holders consists of a conical body portion 16, of rubber, 85 rubber and canvas, or similar material, and a central calk 17, of steel, which passes therethrough, and the said calk-holders and calks are held in place by nuts 18, countersunk in the top of the body portion of the pad, as 90 clearly shown in Fig. 5, and into which the calks 17 are screwed. These calk-holders and calks are intended for use only when it is slippery or when the ground is frozen, and they may be removed or placed in position 95 whenever desired, it being understood that the removal of or the placing of the same in position must be accomplished before the shoe is put on the foot, at which time the top portion 7^a of the pad may be separated from 100 the body portion of the pad, if desired.

The shoe is secured to the foot in the usual manner by nails driven through suitable holes at 19, and this operation will also secure both

parts of the pad to the foot, as will be readily understood; but the top portion 7^a of the pad may be permanently secured to the body portion of the pad, if desired.

- 5 The various holes or openings 10 and 13 and the holes or openings 8^a in the central cushion 8', together with the holes or openings 12 in the central portion of the top part of the pad, serve to fully ventilate the foot
10 at all times, and the groove 9 in the top of the body portion of the pad operates to prevent the air holes or openings 10 and 11 from becoming clogged.

By means of my improved pad the feet of a
15 horse will be securely protected at all times, the pad serving to fully cushion and protect the foot, and the animal will also be prevented from slipping when the ground is frosty or frozen.

20 My invention is not limited to the means herein shown and described for holding the detachable calks in the pad, as many other devices may be employed for this purpose; nor is my invention limited to the form and
25 construction of detachable calks as herein described nor to the material of which the same is composed, and many changes in and modifications of the general construction of my improved horseshoe-pad and the various
30 parts thereof may be made without departing from the spirit of my invention or sacrificing its advantages.

Having fully described my invention, what I claim as new, and desire to secure by Letters
35 Patent, is—

1. A pad for horseshoes, comprising a central body portion adapted to fill the shoe, a top portion of leather which overlaps the central body portion of the pad and the shoe, the
40 body portion of the pad being also provided centrally with a cushion which is covered by the top portion of the pad, said top portion of the pad and said body portion and the central cushion being perforated, substantially
45 as shown and described.

2. A horseshoe-pad composed of rubber or similar material and adapted to fill the shoe and provided with a top portion of leather which overlaps the pad and the shoe, the body
50 portion of the pad being also provided with detachable calk-holders and calks, substantially as shown and described.

3. A horseshoe-pad comprising a body por-

tion which is adapted to fill the shoe, a top portion which overlaps the body portion and 55 the shoe, a central cushion which is also covered by the top portion, said body portion being provided in the top thereof with a groove around said cushion, and said top and body portions with perforations which communicate with said groove, substantially as shown and described.

4. A horseshoe-pad comprising a body portion which is adapted to fill the shoe, a top portion which overlaps the body portion and 65 the shoe, a central cushion which is also covered by the top portion, said body portion being provided in the top thereof with a groove around said cushion, and said top, and body portions with perforations which communicate with said groove, the said pad being also provided just within the shoe with perforations substantially as shown and described.

5. A horseshoe-pad comprising a body portion which is adapted to fill the shoe, a top 75 portion which overlaps the body portion and the shoe, a central cushion which is also covered by the top portion, said body portion being provided in the top thereof with a groove around said cushion, and said top and body 80 portions with perforations which communicate with said groove, the said pad being also provided just within the shoe with perforations, and the top portion of the shoe and the central cushion being also perforated, 85 substantially as shown and described.

6. A horseshoe-pad provided with elastic and detachable calk-holders which are set thereinto, and calks detachably secured in said holders, substantially as shown and de- 90 scribed.

7. A horseshoe-pad composed of top and bottom portions, the bottom portion being provided with a groove in the top thereof and both of said portions being provided with 95 perforations or openings which communicate with said groove, substantially as shown and described.

In testimony that I claim the foregoing as my invention I have signed my name, in presence of the subscribing witnesses, this 7th day of May, 1901.

HENRY CHRISTOPHER.
